CLAIM

The ornamental design for a control grip, as shown and described.

DESCRIPTION

FIG. 1 is a top, rear, left perspective view of a control grip according to our new design;

FIG. 2 is a top, rear, right perspective view thereof;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top view thereof; and,

FIG. 8 is a bottom view thereof.

Applicant regards the disclosed design as including all features shown in the accompanying drawings, including FIGS. 1-8. The broken line representations in the figures show unclaimed environment or boundaries, and thus form no part of the design as presently claimed.

The nature of this product is a control grip or portion thereof, such as for use by an operator during operation of a work vehicle for operator stabilization and/or machine control purposes.
